UNITED STATES PATENT OFFICE

ALFRED WOODWARD KENT, OF LEICESTER, ENGLAND, ASSIGNOR TO WILLIAM SPIERS LIMITED, OF LEICESTER, ENGLAND, A BRITISH COMPANY

KNITTING MACHINE

Application filed October 26, 1931, Serial No. 571,240, and in Great Britain November 26, 1930.

This invention relates to circular knitting machines of the axially opposed needle cylinder type furnished with independent needles and has for its object to provide in such machines improved means for producing patterned fabric by reverse plating, i. e. reversing the relative position of ground and plating yarns fed to the needles.

To enable the invention to be more clearly and readily understood I will describe, with reference to the accompanying drawings, a specific example as applied to a circular rib knitting machine of the superposed rotary needle cylinder type equipped with double ended needles operated by sliders.

In the drawings,

Figure 1 is a sectional rear elevation of the upper part of a machine of this type showing said example of the invention applied thereto, the section being taken on line I—I of Figure 11.

Figure 2 is a perspective view on an enlarged scale of a few of the jacks and needles co-operating in the production of normal and reverse plated loops.

Figures 3 and 4 are side views on an enlarged scale of a jack and needle co-operating for normal plating.

Figures 5 and 6 are similar views showing a jack and needle co-operating for reverse plating.

Figure 7 is a side elevation of the yarn engaging ends of two jacks which differ in respect of the lengths of the back butts thereon.

Figure 8 is a sectional plan view taken on line VIII—VIII of Figure 1 but with the needles and needle cylinder omitted.

Figure 9 is an enlarged view of part of Figure 8.

Figure 10 is a side elevation of a mechanism for controlling a cam which is provided for nullifying the action of the jack selecting means.

Figure 11 is a plan of part of the machine showing the jack selecting cams, the drum for operating the cams and pawl and ratchet mechanism for rotating the drum, parts being broken away for clearness.

Figure 12 is a front elevation of mecha-

nism employed to control the said pawl and ratchet mechanism.

Figures 1, 8 and 11 are drawn to a larger scale than Figures 10 and 12.

According to the illustrative embodiment 55 of the invention I provide a circular series of jacks 1 mounted respectively in grooves 2 in a cylinder 3 concentric with the top needle cylinder 4. The jack cylinder 3 is rotatably mounted on a bearing sleeve 5 attached to the top plate 6 of the machine and is supported by a ball bearing 7 carried by a post 8 concentric with the fixed sleeve 5. In addition to carrying the jacks, the jack cylinder 3 has the top needle cylinder 4 secured thereto externally, e. g. by means of screws 4a, so as to leave the upper portions of the jacks exposed, as shown in Figure 1, and so that the grooves 2 alternate with the needle grooves 4b in the needle cylinder. 70 Each of the jacks has at its lower end a hook-like yarn engaging extremity 9 which extends radially from the jack cylinder below the lower end of the top needle cylinder preferably through a verge 10 fitted in the lower 75 end of the needle cylinder to prevent sideways flexion of the yarn engaging extremity. The yarn engaging extremity of each jack therefore works between two adjacent needles, as shown in Figure 2. Furthermore, 80 each jack has a fulcrum point 11 or equivalent at the back so as to enable it to rock in its groove, and also has one or more front butts 12 above the fulcrum for engagement by one or another of a series of selecting cams 85 13, and a depending butt 14 or bent projection at or near the lower end for engagement with a cam ring 15 secured to the central post 8 concentrically with the jack cylinder. 90

The selecting cams 13 are arranged on a vertical pivot 16 parallel with the cylinder axes and above the top cylinder for action on the exposed front butts 12 of the jacks, and a pin drum 17, racked round by pawl and ratchet mechanism hereinafter particularly described, is provided for selective action on the cams. The drum has the pins 18 prearranged therein according to pattern requirements, said pins being merely pushed 100

in the drum and held therein by a cover 19 formed with slots 20 corresponding with the cams 13 each of which is furnished with a projection 13a, said projections extending through the slots respectively for contact with the pins. The width of each slot is less than the diameter of a pin so that it is not possible for any pins to leave the drum through the slots. It will be understood that 10 during the production of plated knitted fabric two yarns *a* and *b* are fed in usual normal plating relation i. e. with the yarn *a* somewhat above and in front of the yarn *b*, in any usual or convenient manner. The upper 15 yarn *a* is normally the back or ground yarn and the other yarn *b* is the front or face yarn of normal plating. When a cam or cams is or are rendered operative by a pin or pins in the drum the corresponding jack or 20 jacks is or are pressed inwards above the fulcrum or fulcrums as represented at the right of Figure 1, with the result that the lower extremity or extremities is or are projected radially as represented on the right of Figure 1 and at A in Figures 8 and 9 so that the hook-like formation 9 or formations is or 25 are brought on to the outside of the yarn *a* as shown by dot and dash lines in Figure 3.

It will of course be understood that the 30 relation between the jacks and the yarns preparatory to the selective action is such that the lower extremities of the selected jacks are projected without catching the yarn *a*.

Adjustably mounted in a bracket 21 attached to the top plate 6 is a cam 22 (Figure 1) adapted to engage the upper butt-like ends 23 of all of the jacks after the selective action so that the latter are pushed downwards in conjunction with the descent of 40 the needles 24 preparatory to forming loops.

The selective jack or jacks is or are moved inwards at the lower end or ends by the action of the aforesaid cam ring 15 on the butt or butts 14 at or substantially at the end 45 of the descent of the jacks as aforesaid with the result that the yarn *a* is engaged by the said jack or jacks and it is displaced from its normal position (see Figure 3) in front of the yarn *b* to a position toward the rear of the said yarn *b*, as represented at B in Figure 2 and in Figure 5, whereby the needle or needles taking the yarns in this relation form a reversely plated loop or loops, as represented in Figure 6. Where a jack is not 50 operated in this way, so that the yarns remain in normal plating relation as shown in Figure 3, the corresponding needle forms an ordinary plated loop, as represented in Figure 4. The extremities 9 of the jacks 55 uninfluenced by the selecting cams pass inside the yarn *a* as shown at C in Figure 2 and by full lines in Figure 3, so that the outer edges 9a maintain said yarn in its normal position actually pushing it outwards slightly as the needles descend to take the yarns.

From the foregoing description it will be observed that by reason of the operation of the jacks as aforesaid the engagement between the yarns and the jacks after the selective action is maintained as long as possible so that not only is the plating reversed definitely by the selected jacks but is also definitely kept to normal where required by the non-selected jacks, consequently the change or changes from normal plating to 70 reverse plating is or are clearly defined. Subsequently the jacks are raised to their normal position by another cam 25 acting on the upper ends of the jacks.

Referring to Figure 8, it will be observed that for substantially half of its circumference the wall of the cam ring 15 is of such a thickness as to occupy completely the space 26 between the lower end of each jack and its butt or projection 14 as shown on the left of Figure 1. A prominence 27 is suitably formed on the cam ring to project the lower extremities of the jacks momentarily just prior to selection by the cams 13 to keep the verge 10 and the spaces between adjacent needles clear of fluff and the like which accumulates during knitting.

The wall of the cam ring is thinned down at 28 on the inside thereof for a suitable distance to allow for the outward movement of the lower extremities of selected jacks under the action of one or more of the cams 13, as represented in Figures 8 and 9, and a notch 29 is provided in the top edge of said ring to permit of the downward movement of the jacks by the cam 22. The wall 28 of the cam ring 15 may be formed in any suitable way to effect the slight outward movement of the non-selected jacks whereby the edges 9a are caused to press upon the yarn *a* at the required time and push it outwards slightly as previously alluded to herein. It will be understood that following the selective action the selected jacks are retracted to change the position of the yarns *a* and *b* as the result of the engagement of the butts 14 with the inner face 28a of the wall of the cam ring 15, as shown in Figure 8.

Means may be provided to function in opposition to the selecting cams 13 to nullify the action thereof at any time during the knitting action so that although jacks may be selected as aforesaid the selected jacks are retracted before engagement with the yarn *a* so that the positions of the yarns *a* and *b* are not changed. In this way horizontal striping may be effected by producing one or more courses of plain plating alternately with one or more courses of reverse plating, or plain plated courses may be produced alternatively with courses containing reverse plated loops forming patterns, according to requirements. In the application of the invention to a machine for producing seamless hosiery the said means may be em- 115 120 125 130

ployed to counteract the selective action during the production of rib tops, and when changes are made from rotary to reciprocatory motion for knitting heels and toes. In addition to this provision may be made for 5 counteracting the selective action in respect of the jacks associated with the needles which knit the foot bottom during the production of a foot, thereby to produce a plain foot bottom.

10 According to the preferred form of construction and arrangement, some of the jacks are provided with back butts 14a which are longer than the back butts 14, see Figure 7, and a cam 30 is provided for action on the butts 14, 14a. This cam is fixed on an arm 31 attached to a vertically slidable rod 32 normally held raised by a spring 33 interposed between a collar 33a and the bottom of a recess in a support 8a for the rod 8. 15 When the cam 30 is in this position it acts upon the butts 14, and 14a alike, of any jacks operated by the selecting cams 13, thereby withdrawing the lower extremities of these 20 jacks before they engage the yarn a. The cam 30 is moved downward to avoid either the butts 14 or all of the butts according to requirements by pressing the rod 32 down against the action of the spring 33. This 25 is effected by means of a lever 34 connected by a push rod 35 with another lever 36 acted upon by cam bits or like elements 37, 37a on the pattern drum 38 of the machine.

30 The cam 30 projects through a slot 39 in the cam ring 15, and as the result of intermittent rotation of the pattern drum in the usual way is moved up or down by the aforesaid cam-operated and spring-controlled connections into and out of the path of the butts or projections 14 and/or 14a on the selected 35 jacks.

40 In the application of this embodiment of the invention to a machine for knitting seamless hosiery substantially one half of the jacks, i. e. those associated with the needles which knit the foot bottom, have the longer back butts 14a and the cam 30 may be moved into three positions by its controlling means, i. e. into the lowest position shown in Figure 45 1 to miss all the butts 14 and 14a, into a somewhat higher position to engage the long butts only, and the highest position to engage all the butts. For example the cam 30 may be depressed into its lowest position by the 50 cam 37 during the knitting of the leg portion of a stocking so that all round pattern effects can be produced. If, however, it is desired to produce a plain foot bottom the pattern drum is racked round so that the cam 55 bit or element 37 releases the lever 36 which thereupon drops on to the cam bit or element 37a whereby the cam 30 is raised slightly by the spring 33 into the path of the long butts 14a so that any long butt jacks which may 60 65 have been selected as aforesaid are restored

to the plain plating position (Figure 3) before they reach the plating yarn, while short butt jacks selected to reverse plate function in the required manner. During the knitting of the heels, toes and rib tops the cam 30 may be raised to its highest position by freeing the lever 36 from the cam bit 37a so that the cam engages the back butts of all the selected jacks, as represented in Figure 9, to nullify the selective action. At these times another yarn or other yarns may if desired be substituted for one or both of the plating 70 75 yarns a, b.

80 The pawl and ratchet mechanism for operating the pin drum 17 is actuated by means of a cam 40 attached to a gear wheel 3a keyed on the jack cylinder 3, which is driven in a manner similar to that usually adopted for driving the top cylinder in machines of the type concerned and therefore not shown. The pawl 41 is mounted on one end of a lever 42 controlled by a spring 42a and pivotally mounted centrally on the drum spindle or stud 43, a roll 44 being provided at the other end of the lever for engagement with the cam 40. Preferably two ratchet wheels 45 and 46 are provided each having teeth of the same pitch, but the wheel 46 has alternate deep and shallow teeth as shown in Figure 11 and is freely mounted on the spindle 43 so that, by shifting the pawl axially, for example by removing the washer 47 to cause said pawl to engage either the wheel 45 or both wheels, the drum may be racked round at every course or at alternate courses according to requirements. The wheel 46 is slightly larger in diameter than the wheel 45 and it will be understood that with the pawl in a position to engage both ratchet wheels, when the pawl is engaging a shallow tooth on the wheel 46, it does not engage the corresponding tooth of the wheel 45 so that the wheel 46 is moved idly and the wheel 45 is not moved. When on the next stroke of the 90 95 pawl the latter engages a deep tooth on the wheel 46 it also engages the corresponding tooth on the wheel 45 and thereby rotates both wheels and consequently the pin drum. The stud 43 is adjustably mounted relatively to the jack cylinder or sleeve in a slot 48 in the top plate 6, and it may have associated therewith braking means such as a friction pad 49 pressed upon the drum by a spring 49a. In addition to or instead of the pad 49 a check pawl or detent 50 may be provided for example in a housing 50a on the cover 19 in company with a spring 50b. The pawl lever 42 is centrally pivoted concentrically with the drum the arms thereof extending 100 105 through openings 19a and 19b respectively in the cover 19. The pawl 41 also extends through the opening 19b in the cover 19 to engage the ratchet wheels. These openings 110 115 are above the series of pins 18 so that there

is no likelihood of escape of pins through said openings.

The racking of the pattern drum may be controlled from a timing chain or equivalent so that it can be caused to rack or to dwell on a particular selection as required. To this end suitable means may be employed for rendering the pawl and ratchet mechanism inoperative for any desired number of courses.

10 Conveniently I provide a vertically movable rod 51 (Figures 11 and 12) moved in one direction by a spring 52 and in the other direction by one or more dogs such as 53 on the existing timing chain 54 of the machine through the medium of levers 55, 56, a link 57 and a lever 58. The rod 51 is moved when required into the path of the oscillating pawl lever 42 so as to hold the latter with the roller 44 out of the path of the cam 40.

20 The support 8a for the shaft or post 8 may be mounted in the top plate of the machine to enable the cam ring 15 and associated parts to be set properly in relation to the selecting cams and/or the feeder of the machine. For 25 this purpose the support 8a is furnished with a lug for engagement by set screws 60 carried in ears or lugs 61 on the top plate as shown in Figure 11.

Instead of adjusting the pawl 41 entirely 30 manually as and for the purpose previously alluded to suitable mechanical means may be provided for effecting the requisite relative axial movement between the pawl and the ratchet wheels 45 and 46.

35 It will be understood that once a series of jacks has been arranged in the cylinder, a large variety of patterns can be made with one set out of the jacks by setting out the patterns in the pattern drum merely by pushing pins into appropriate holes in the drum, the latter being furnished circumferentially with several parallel rows of reamed holes, regularly spaced in each row with a pitch corresponding to the pitch of the teeth of the 40 ratchet wheels.

45 A feature of construction is that each jack has its butt-like end 23 stepped and formed with inclines as shown at 23a in Figure 1 and the edge 22a of the cam 22 is backed off to suit the inclines so that during the descent of the jacks under the action of the cam the outer inclines of the selected jacks and the inner inclines of the non-selected jacks make contact with the backed-off edge 22a of the cam 22 whereby during descent as aforesaid the jacks are maintained in the positions determined by the selecting means. This construction provides a face-to-face contact between the cam edge 22a and the opposing ends 50 of the jacks in either position of the latter and such wear as may take place is evenly distributed over the inclines, and/or the cam edge. At or near the lower end the backed off edge of the cam 22 merges into a rounded 55 portion which facilitates outward movement

of the butt-like ends 23 when the lower ends of the selected jacks are retracted by the action of the cam ring 15 as previously described herein.

The invention is applicable to machines of the type herein referred to generally and while it is mainly the intention to apply the invention to machines of this type wherein superposed needle cylinders rotate and reciprocate within corresponding cam boxes, the invention is not to be regarded as limited in this respect as it may be applied to machines of the same type wherein the cylinders merely rotate and also to machines wherein the cylinders are stationary within rotary cam boxes which may reciprocate or not.

What I claim then is:—

1. In a circular knitting machine, double axially opposed needle cylinders, independent needles in said cylinders, means for feeding yarns to the needles in plating relation, yarn engaging jacks arranged to extend in an axial direction with respect to the needle cylinders alternately with the associated needles, said jacks being movable radially with respect to the axes of the cylinders, means operative selectively upon the jacks whereby selected jacks are moved radially into a yarn engaging position, and means operative upon the selected jacks to move same in the opposite direction whereby said jacks are caused to engage one of said yarns and to move the other positively in relation to the other yarn thereby changing the relative positions of the yarns and reversing the plating.

2. In a circular knitting machine, double axially opposed needle cylinders, independent needles in said cylinders, means for feeding yarns to the needles in plating relation, yarn engaging jacks arranged to extend in an axial direction with respect to the needle cylinders, means operative upon the jacks selectively whereby selected jacks are caused to function to change the normal relative positions of the yarns, and means for imparting lengthwise movement to the jacks conjointly with and in the direction of the loop drawing movement of the needles for the purpose of maintaining the jacks in engagement with the yarns thereby to keep control of the yarns during said movement of the needles.

3. In a circular knitting machine, double axially opposed needle cylinders, independent needles in said cylinders, means for feeding yarns to the needles in plating relation, yarn engaging jacks arranged to extend in an axial direction with respect to the needle cylinders, means whereby the jacks are moved selectively into a yarn engaging position, means operative upon the selected jacks to cause same positively to change the relative positions of the yarns, and means for imparting lengthwise movement to the jacks conjointly with and in the direction of the loop drawing movement of the needles for

the purpose of maintaining the jacks in engagement with the yarns thereby to keep control of the yarns during said movement of the needles.

4. In a circular knitting machine, double axially opposed needle cylinders, independent needles in said cylinders, means for feeding yarns to the needles in plating relation, yarn engaging jacks arranged to extend in an axial direction with respect to the needle cylinders alternately with the associated needles, said jacks being movable radially with respect to the axes of the cylinders, means operative selectively upon the jacks whereby selected jacks are moved radially into a yarn engaging position, means operative upon the selected jacks to move same in the opposite direction whereby said jacks are caused positively to change the normal relative positions of the yarns, and means for imparting lengthwise movement to the jacks conjointly with and in the direction of the loop drawing movement of the needles for the purpose of maintaining the jacks in engagement with the yarns thereby to keep control of the yarns during said movement of the needles.

5. In a circular knitting machine, double axially opposed needle cylinders, independent needles in said cylinders, means for feeding yarns to the needles in plating relation, yarn engaging jacks arranged to extend in an axial direction with respect to the needle cylinders, said jacks being mounted pivotally and slidably, means operative upon the jacks selectively whereby selected jacks are caused to function to change the normal relative positions of the yarns, and means for imparting lengthwise movement to the jacks conjointly with and in the direction of the loop drawing movement of the needles for the purpose of maintaining the jacks in engagement with the yarns thereby to keep control of the yarns during said movement of the needles.

6. In a circular knitting machine, double axially opposed needle cylinders, independent needles in said cylinders, means for feeding yarns to the needles in plating relation, yarn engaging jacks arranged to extend in an axial direction with respect to the needle cylinders, said jacks being mounted pivotally and slidably, means whereby the jacks are moved selectively into a yarn engaging position, means operative upon the selected jacks to cause same positively to change the relative positions of the yarns, and means for imparting lengthwise movement to the jacks conjointly with and in the direction of the loop drawing movement of the needles for the purpose of maintaining the jacks in engagement with the yarns thereby to keep control of the yarns during said movement of the needles.

7. In a circular knitting machine, superimposed needle cylinders, independent

needles adapted to work in said cylinders, means for feeding yarns in plating relation, a circular series of yarn engaging jacks, a longitudinally grooved cylinder in which said jacks are arranged for movement individually, said jack cylinder being arranged concentrically with the needle cylinders so that the jacks extend in a vertical direction with their lower extremities which are formed for yarn engagement alternating with the needles, means whereby the jacks are moved selectively into a yarn engaging position, and means operative upon the selected jacks so that the yarn engaging extremities thereof function positively to change the normal relative positions of the yarns thereby to effect reverse plating.

8. In a circular knitting machine, superimposed needle cylinders, independent needles adapted to work in said cylinders, means for feeding yarns in plating relation, a circular series of yarn engaging jacks, a longitudinally grooved cylinder in which said jacks are arranged for movement individually, said jack cylinder being arranged concentrically with the needle cylinders so that the jacks extend in a vertical direction with their lower extremities which are formed for yarn engagement alternating with the needles, means whereby the jacks are moved selectively into a yarn engaging position, means operative upon the selected jacks so that the yarn engaging extremities thereof function positively to change the normal relative positions of the yarns thereby to effect reverse plating, and means for imparting axial movement to the jacks in conjunction with and in the same direction as the loop drawing movement of needles whereby to keep control of the yarns during said movement of the needles.

9. In a circular knitting machine, axially opposed needle cylinders, independent needles in said cylinders, means for feeding yarns to the needles in plating relation, yarn engaging jacks arranged to extend in an axial direction with respect to the needle cylinders, said jacks being furnished with yarn engaging extremities disposed at right angles to the needles, means whereby said jacks are moved selectively into a yarn engaging position, means for moving the selected jacks radially with respect to the needles to cause the yarn engaging extremities thereof to reverse the normal relative positions of the yarns, and means for moving the jacks endwise conjointly with and in the same direction as the loop drawing movement of the needles so as to maintain the jacks in engagement with the yarns thereby to keep the yarns under control during said movement of the needles.

10. In a circular knitting machine axially opposed needle cylinders, independent needles in said cylinders, means for feeding yarns

to the needles in plating relation, contrastingly formed yarn engaging jacks arranged to extend in an axial direction with respect to the needle cylinders, a series of jack selecting cams whereby jacks are selected to function to change the normal relative positions of the yarns, means for automatically selecting said cams for action upon the jacks according to pattern requirements, a cam for operating the selected jacks whereby to cause same positively to change the normal relative positions of the yarns, and a cam for imparting axial movement to the jacks conjointly with and in the same direction as the loop drawing movement of the needles so as to maintain the jacks in engagement with the yarns thereby to keep the yarns under control during said movement of the needles.

11. In a circular knitting machine, double axially opposed needle cylinders, independent needles in said cylinders, means for feeding yarns to the needles in plating relation, yarn engaging jacks arranged to extend in an axial direction with respect to the needle cylinders, means whereby the jacks are selectively moved radially outwards with respect to the needles into a position to engage the back yarn of normal plating, and means for moving the selected jacks in the opposite direction to change the position of said yarn in relation to the front yarn of normal plating, in order to produce reverse plating.

12. In a circular knitting machine, double axially opposed needle cylinders, independent needles in said cylinders, means for feeding yarns to the needles in plating relation, yarn engaging jacks arranged to extend in an axial direction with respect to the needle cylinders, means whereby the jacks are selectively moved radially outwards with respect to the needles into a position to engage the back yarn of normal plating, means for moving the selected jacks in the opposite direction to change the position of said yarn in relation to the front yarn of normal plating, in order to produce reverse plating, said jacks having yarn engaging extremities such that the extremities of the non-selected jacks engage the back yarn of normal plating and maintain said yarn in its normal position while the selected jacks function for reverse plating.

13. In a circular knitting machine, double axially opposed needle cylinders, independent needles in said cylinders, means for feeding yarns in plating relation to the needles, yarn engaging jacks arranged to rock for the purpose of changing the relative positions of the yarns, each jack being furnished with a transverse yarn engaging extremity adapted to operate between adjacent needles with a movement radially with respect to the needle circle, and, for selecting purposes, with at least one butt on one edge, selecting means for engagement with said butt where-

by the jack is rocked in one direction into a yarn engaging position, said jack being furnished with another butt on the other edge, and a cam for engagement with said other butt whereby the jack is rocked in the opposite direction to change the relative positions of the yarns.

14. In a circular knitting machine superposed needle cylinders, independent needles in said cylinders, means for feeding yarns to the needles in plating relation, a circular series of jacks, a grooved cylinder in which said jacks are pivotally and slidably mounted, each jack being furnished with a hook-like yarn engaging extremity, a fulcrum, at least one front butt above the fulcrum and a rear butt below the fulcrum, selecting means arranged above the fulcrum for action on the front butts of the jacks whereby selected jacks are pressed inwards above the fulcrum so that their yarn engaging extremities are projected radially outwards with respect to the needles into a yarn engaging position on the outside of the plating yarns, and cam means which by action on the rear butts move the selected jacks in the opposite direction whereby said jacks are caused to engage the ground yarn of normal plating and shift the latter from its normal position in front of the plating yarn to a position in the rear of said yarn, for the purpose described.

15. In a circular knitting machine, double axially opposed needle cylinders, independent needles in said cylinders, means for feeding yarns in plating relation to the needles, yarn engaging jacks arranged to rock for the purpose of changing the relative positions of the yarns, each jack being furnished with a transverse yarn engaging extremity adapted to operate between adjacent needles with a movement radially with respect to the needle circle, and, for selecting purposes, with at least one butt on one edge, selecting means for engagement with said butt whereby the jack is rocked in one direction into a yarn engaging position, said jack being furnished with another butt on the other edge, a cam for engagement with said other butt whereby the jack is rocked in the opposite direction to change the relative positions of the yarns, and a cam positioned for engagement with the opposite extremity of each jack to impart endwise movement thereto in conjunction with the loop drawing movements of the needles so as to maintain control over the yarns during said movement of the needles.

16. In a circular knitting machine superposed needle cylinders, independent needles in said cylinders, means for feeding yarns to the needles in plating relation, a circular series of jacks, a grooved cylinder in which said jacks are pivotally and slidably mounted, each jack being furnished with a hook-like yarn engaging extremity, a fulcrum at

least one front butt above the fulcrum and a rear butt below the fulcrum, selecting means arranged above the fulcrum for action on the front butts of the jacks whereby selected jacks are pressed inwards above the fulcrum so that their yarn engaging extremities are projected radially outwards with respect to the needles into a yarn engaging position on the outside of the plating yarns, 5 cam means which by action on the rear butts move the selected jacks in the opposite direction whereby said jacks are caused to engage the ground yarn of normal plating and shift the latter from its normal position in front 10 of the plating yarn to a position in the rear of said yarn, and a cam positioned for engagement with the opposite extremity of each jack to impart endwise movement thereto in conjunction with the loop drawing movements of the needles so as to maintain control over the yarns during said movement of the needles.

17. In a circular knitting machine, double axially opposed needle cylinders, independent 25 needles in said cylinders, means for feeding yarns to the needles in plating relation, yarn engaging jacks arranged to extend in an axial direction with respect to the needle cylinders, means operative upon the jacks 30 selectively whereby selected jacks are caused to function to change the normal relative positions of the yarns, said jacks including some with formation of one length and others with similar formations of another 35 length, a movable cam adapted to operate on said formations in opposition to the selecting means so as to counteract the selective action, and means for automatically controlling said cam.

40 18. A yarn engaging jack comprising a stem, a transverse shouldered yarn engaging formation at one end of the stem, at least one butt on one edge of the stem for engagement with a selecting cam, said stem having 45 a fulcrum point on the opposite edge, and another butt on the said opposite edge of the stem for engagement with an actuating cam, for effecting reverse plating in the production of plated knitted fabric.

50 19. A yarn engaging jack comprising a stem, a yarn engaging formation at one end of the stem, and at least one butt on the stem for engagement with a selecting cam, said stem having a fulcrum point on the opposite edge and inclined edges at the opposite end for engagement with a cam for imparting endwise movement to the jack, and another butt on said opposite edge of the stem for engagement with an actuating cam, said jack 55 being adapted to effect changes in plating in the production of plated knitted fabric.

In testimony whereof I affix my signature.
ALFRED WOODWARD KENT.
